(57) **CLAIM**

The ornamental design for a surface configuration of a vehicle body and/or toy, as shown and described.

DESCRIPTION

FIG. 1 is a left, front perspective view of a surface configuration of a vehicle body and/or toy according to my novel design, the right, front perspective view being mirror symmetrical

FIG. 2 is a left side view of the surface configuration of a vehicle body and/or toy according to my novel design;

FIG. 3 is a right side view of the surface configuration of a vehicle body and/or toy according to my novel design;

FIG. 4 is a left, rear perspective view of the surface configuration of a vehicle body and/or toy according to my novel design, the right, rear perspective view being mirror symmetrical;

FIG. 5 is a front view of the surface configuration of a vehicle body and/or toy according to my novel design;

FIG. 6 is a rear view of the surface configuration of a vehicle body and/or toy according to my novel design; and,

FIG. 7 is a top view of the surface configuration of a vehicle body and/or toy according to my novel design.

The broken lines included depict environment and are not part of the claimed design.
